2 SHEETS-SHEET 2.

UNITED STATES PATENT OFFICE.

WILLIAM P. DAY, OF CLEVELAND, OHIO, ASSIGNOR TO INTERNATIONAL STEEL TIE COMPANY, OF CLEVELAND, OHIO, A CORPORATION OF DELAWARE.

RAIL-SUPPORT.

1,066,085.

Specification of Letters Patent.

Patented July 1, 1913.

Application filed January 20, 1912. Serial No. 672,443.

To all whom it may concern:

Be it known that I, WILLIAM P. DAY, citizen of the United States, residing at Cleveland, in the county of Cuyahoga and State of Ohio, have invented certain new and useful Improvements in Rail-Supports, of which the following is a specification.

My invention relates to railway supports or sleepers, and is designed with special reference to the composite rail support illustrated and described in my Patent, No. 1,000,329, dated August 8, 1911, though the invention is capable of use, in certain details, with other forms of rail support.

15 The primary object of my invention is to provide a simple, durable and thoroughly efficient railway tie or support, having relatively few parts, and these of such character that the tie as a whole may be readily assembled, and when assembled will give a maximum of strength and rigidity to the complete tie.

20 A further object is to so form the tie that the tie or support, and therefore the track itself, can not become "center-bound," a fault which is present in nearly all tie constructions, and which it is particularly desirable to eliminate.

25 A further object in connection with the above, is to provide a tie wherein a maximum of rigid support is given to each rail, but wherein the middle portion of the tie between the rails is made relatively yieldable, thus providing for an elasticity in the 30 track found to be necessary for smooth running and long wear.

35 A still further object is to provide a tie with means which will cause the tie to have a positive engagement with the road bed, thus preventing any lateral deflection of the track as a whole under strain.

40 Another object is to provide a tie formed with channel and angle irons, and provide in this connection means whereby the water 45 from the surface of the tie may be carried off and deflected from the said angle and channel irons, and to provide for proper drainage, not only for the water falling upon the face of the tie, but also provide 50 proper drainage for the space between the ties so that the water will be carried off from the track ballast.

Another object is to provide a composite

tie made up of a steel skeleton frame, concrete filling and wooden pillow blocks, so 55 arranged as to secure the greatest possible economy in the use of wood with a maximum of solidity beneath the rails, and to provide in combination with these parts rail supporting pillow blocks, easily put in 60 place and easily removed, the parts being of standard materials, capable of being produced by any properly equipped steel mill, and without the necessity of special tools, and so constructed that the skeleton frame 65 of the tie may be put together, either at the mill or at the track side, and that the concrete filling may be placed in position after the skeleton structure of the tie has been put in place.

70 Other objects and advantages will appear in the course of the following description.

My invention is illustrated in the accompanying drawings wherein:

Figure 1 is an end elevation of a track 75 support constructed in accordance with my invention. Fig. 2 is a plan view of the track structure shown in Fig. 1, the rail and rail supporting pillow blocks at one side of the structure being removed. Fig. 3 is 80 a transverse section of a track support on the line 3—3 of Fig. 2. Fig. 4 is a transverse section and elevation of the track support shown in Fig. 2. Fig. 5 is a perspective view of one end of my improved track 85 support. Fig. 6 is a perspective detail view of the rail clamping means.

90 Corresponding and like parts are referred to in the following description and indicated in all the views of the accompanying drawings by the same reference characters.

95 Referring to these drawings, it will be seen that my improved tie or sleeper comprises the spaced, parallel, transversely extending beams 1, these beams being shown as I-beams, it being understood, however, that beams of any other desired cross sectional form might be used. These beams are connected in spaced relation with each other by a pair of spaced angle irons 2 and 2^a at 100 each end of the tie. These angle irons have their horizontal flanges extending in opposite directions so as to provide between each pair of angle irons a seat for pillow blocks 9, as will be later described. Also arranged 105 at opposite ends of the beams 1 are the op-

2
positely disposed pairs of angle irons 3 and 3^a. These angle irons are connected to the base flanges of the beams 1 and have their vertical flanges extending downward. It is to be especially noted in this connection that the angle irons 2^a are set inward of the extremities of the beams 1, and that the angle irons 3^a are set at the extremities of the beams 1, and hence that there is an angular relation between the angle irons 2^a and the angle irons 3^a, but that the inner angle irons 3 are disposed immediately below the inner angle irons 2.

10 The space defined by the beams 1, the angle irons 2 and 2^a, and the angle irons 3 and 3^a is intended to be filled with concrete or other artificial stone, designated 4, and embedded in this concrete are a plurality of pillow blocks 5 which extend parallel to the beams 1 and are spaced from each other. 15 As shown, there are three of these pillow blocks 5, two of them being arranged immediately adjacent to the inside faces of the channel irons 1, and the other being disposed midway between the first pair of blocks. It will be seen from Fig. 4 that these pillow blocks are embedded in the concrete but are less in depth than the distance between the upper faces of the channel irons 1 and the lower faces thereof, and that the blocks are spaced from each other by the intermediate concrete 4^a. These pillow blocks 5 preferably extend beneath the angle irons 2 and are preferably in contact with the under faces thereof. 20 25 30 35

It will be seen from Fig. 3, that the angle irons 3 extend down below the concrete filling 4 so that the projecting edges of the vertical flanges of the angle iron will be forced 40 into the road-bed, and that these projecting flanges biting as they do, into the ground will positively prevent any lateral movement of the track structure as a whole. It is to be understood of course that I may use 45 as many of these transverse angle irons 3 as desired, and I have shown one of these transverse angle irons disposed between each pair of the angle irons 3.

While the inside face of the concrete filling 4 beneath the pillow blocks 5 is straight and vertical, as indicated at 6, the outer face of the concrete filling 4 is preferably angularly disposed as at 7, the upper edge of the concrete face being coincident with 50 the outer edge of the angle iron 2^a, while the lower edge of the face is coincident with the corner of the angle iron 3^a. This not only directs all thrust toward the outer ends 55 of the tie structure, but also forms a water shedding face at the ends of the tie. In order to prevent the collection of water upon the faces of the angle irons 2 and 2^a, and to provide for draining off any water which may fall upon the face of the tie, I fill these 60 65 angle irons 2 and 2^a with concrete as at 8,

the face of the concrete being downwardly and outwardly inclined from the upper edge of the angle iron to the lower edge thereof. This concrete filling entirely protects the angle irons 2 and 2^a and serves to rapidly carry off, not only rain water which may fall upon the surface of the track, but also carry off the brine which drips from refrigerator cars, and which is particularly destructive to metallic ties. 75

Resting upon the upper flanges of the beams 1 and held in place between the angle irons 2 and 2^a are the upper pillow blocks 9. Preferably there are a plurality of upper pillow blocks at each end of the rail supporting structure, the concrete filling 4 extending upward between these pillow blocks 9 and the pillow blocks 9 resting solidly upon the pillow blocks 5 below them. It will be noted that these pillow blocks do not extend laterally beneath the channel beams 1, which would render it difficult to put the blocks in place or to replace the blocks, but that both the pillow blocks 5 and the pillow blocks 9 can be very easily inserted. The upper pillow blocks 9 are preferably covered on their lower and side faces with tar so that the space between each pillow block and the side flanges 2 and 2^a and between the under side of the pillow block and the pillow block beneath is filled with tar. The upper pillow blocks 9 are held in place by means of spikes passing through the upper pillow blocks and into the lower pillow blocks 5. Preferably these spikes are screw spikes which will be later described. It will be seen that the upper pillow blocks not only afford a yielding support for the rail, but also entirely insulate the rail from the metallic skeleton of the tie, thus fitting this rail supporting structure to be used upon roads having electrical signal systems. 100 105 110

The rails are preferably held to the ties by means of the screw spikes shown in Fig. 6. In this figure, 10 designates a headed spike having screw threads formed upon its shank, and 11 designates a rail clamping plate perforated for the passage of the spike and having a deflected portion 12 adapted to engage over the base of the rail. The plate 11 is formed with a prong 13 or tooth which when the screw 10 is screwed home bites into the face of the wooden pillow block 9 and locks the spike securely and prevents any rotation of the plate 12. 115 120 125

It will be seen that the track rails rest directly upon the upper faces of the uppermost pillow blocks and upon the concrete between these upper pillow blocks, thus affording a very solid support for the rails while providing means whereby the rails may be easily held to the tie by spikes engaging the base flange of the rail and passing through the upper pillow blocks and into the lower pillow blocks. 130

It has been found by actual demonstration that ties constructed as before described, are particularly effective in actual use and under the severest service conditions, and that these ties are particularly valuable when disposed beneath a rail joint. In service conditions and where the heaviest rolling stock and locomotives are being used, it is found that there is no depression of the rails at the joint.

Preferably, and in order to thoroughly protect the beams 1, concrete 14 is filled in between the flanges of the channel iron. The concrete preferably extends downward as shown in Fig. 4, the face of the concrete being outwardly inclined so as to form a good drainage surface. It is to be understood, however, that the concrete 14 though it is applied on the outside and inside of the channel irons 1, does not extend beneath the middle portion of the channel irons, but that the space designated A beneath the middle portion of each channel iron remains unfilled with either concrete or ballast so as to prevent the track from being center-bound.

It will be seen that by the construction heretofore described I have provided a tie or rail support of extreme simplicity, made up of standard materials, and of elements easily assembled, that the ends of the tie are solidly supported, while the middle portion of the tie between the rail supporting sections is free. It will also be seen that I have provided means not only for protecting the metallic portions of the tie, but for carrying off any water which may fall thereon, and that I have also provided means projecting below the rail carrying portions of the tie and receiving the entire weight of a train passing over the track which are forced downward into the ground or roadbed, and prevent any lateral movement of the track structure. Further it will be noted that by my construction I provide a concrete support for the upper pillow blocks 9 but provide for holding the upper pillow blocks 9 to the under pillow blocks 5 by means of spikes forced through the upper pillow blocks and into solid engagement with the under pillow blocks, and in this connection it may be further noted that only a minimum of wood is used in this tie, and that the wood sections are so disposed as to secure the best possible support for the rail. Further it will be seen that the uppermost pillow blocks 9 by reason of the fact that they do not extend down below and beneath the angle irons 2 and 2^a, may be readily removed and replaced. Another advantage of extending the concrete filling 4 below the under side of the channel irons 1 and thereby elevating these channel irons, is that a space is left beneath the channel irons 1 whereby drainage may take place from the ballast held between the channel irons, and, as will

be seen in Fig. 4, the space between each pair of ties may be thus thoroughly drained, even where this space is filled with ballast.

What I claim is:

1. A rail support including parallel spaced beams extending transversely of the track, a plurality of spaced angle irons extending between and attached to the upper flanges of the beams, and disposed in pairs, the vertical flanges of each pair being adjacent to each other whereby to form a pillow block seat extending transversely across the support, a plurality of spaced angle irons extending between and attached to the lower flanges of the beams and having downwardly extending flanges adapted to engage the roadbed and prevent lateral shifting of the support, and concrete filling disposed between the parallel beams and between the lowermost spaced angle irons, the downwardly extending flanges of the angle irons projecting below said filling. 70

2. A rail support including parallel beams extending transversely of the track, concrete filling disposed at each end of the tie formed by said beams and between the beams, said filling extending below the lower edge of the beams, transverse members connecting said beams at opposite ends thereof whereby the middle portions of the beams are supported at a height above the base of the concrete filling to permit drainage between the beams. 90

3. A rail support of the character described having a metallic skeleton frame including a concrete filling and reinforcing irons angular in section, certain of said irons having a horizontally and a vertically disposed flange, the vertical flange extending upward from the horizontal flange, the space defined by said flanges on each of said irons being filled with concrete or like material, said concrete so filled in between the flanges having a downwardly inclined water shedding upper face. 100

4. A rail support of the character described, including spaced parallel beams, angle irons connecting and spacing said beams and arranged in pairs adjacent the ends of the beams and having vertically and horizontally disposed flanges, concrete filling the space between the beams and the angle irons of each pair, and concrete filling the space between the horizontal and vertical flanges of the angle iron, the concrete having a downwardly inclined water-shedding face. 115

5. A rail support of the character described, including spaced parallel beams, angle irons attached to the upper flanges of the beams and connecting and spacing said beams, said angle irons being arranged in pairs adjacent the ends of the beams, concrete filling the space between the beams to the level of the upper flanges thereof, and 125

concrete filling the space between the horizontal and vertical flanges of the angle irons, said first named filling having inclined outer faces between the beams forming a continuation of the filling between the flanges of the adjacent angle iron.

6. A rail support of the character described, including spaced parallel beams, angle irons connected to the upper flanges of the beams and connecting and spacing said beams, said angle irons being arranged in pairs adjacent the ends of the beams, angle irons having downwardly extending vertical flanges extending between said beams and attached to the base flanges thereof and arranged in pairs, one of the angle irons of each lower pair being arranged directly beneath one of the upper angle irons, the other angle iron of the first named pair being arranged at the extremity of the beams, concrete filling the space between the beams and between the lower pair of angle irons and extending upward to the under face of the upper pair of angle irons, said filling having an inclined outer end face extending between the lower outer angle iron and the upper outer angle iron, and concrete filling the space defined by the horizontal and vertical flanges of the upper angle irons.

7. A rail support comprising a metallic frame, concrete filling the ends of the frame, a plurality of pillow blocks embedded in the filling at each end of the frame, said pillow blocks extending parallel to the length of the rail support and being spaced from each other by the concrete filling, and rail supporting pillow blocks.

8. A rail support of the character described, including spaced parallel beams, cross bars arranged in pairs at the ends of the beams and holding the same together in spaced relation to each other and connected to the lower flanges of the beams, retaining cross bars connected to the beams above the first named cross bars, concrete filling the space between the first named cross bars and the adjoining portions of the beams and the upper cross bars, a plurality of pillow blocks embedded in the concrete and spaced

from each other by the concrete, the upper faces of said pillow blocks being flush with the upper faces of the beams, and rail supporting pillow blocks.

9. A rail support of the character described, including spaced parallel beams, concrete blocks filling the space between said beams at the ends thereof, retaining bars secured in pairs to the tops of the beams extending transversely thereof and formed with vertically extending flanges, each pair of retaining bars defining a seat for a pillow block, pillow blocks embedded in the concrete filling, the upper faces of said pillow blocks being flush with the upper flanges of the parallel beams, and upper pillow blocks, detachably seated between the flanges of the respective pairs of retaining bars, and means holding the upper pillow blocks to the pillow blocks beneath.

10. A rail support of the character described, including spaced parallel beams, angle irons having downwardly extending flanges arranged in pairs at the ends of the beams and attached to the lower flanges of the beams, retaining angle irons resting upon and attached to the upper flanges of the beams and disposed approximately above the lower angle irons, concrete filling the space between the first named angle irons and the adjoining portions of the beams and the upper angle irons, a plurality of pillow blocks arranged parallel to the beams, spaced from each other, extending beneath the uppermost angle irons and embedded in said concrete filling, rail supporting pillow blocks disposed in the space between the upper retaining angle irons, and concrete filling the space defined by the vertical and horizontal flanges of the upper angle irons, the vertical flanges of the lower pairs of angle irons extending below the concrete filling to engage the roadbed and prevent any lateral movement of the rail support as a whole.

In testimony whereof I affix my signature in presence of two witnesses.

WILLIAM P. DAY. [L.S.]
